UNITED STATES PATENT OFFICE.

VICTOR R. DESPARD, OF VALPARAISO, INDIANA, ASSIGNOR TO MCGILL MANUFACTURING COMPANY, OF VALPARAISO, INDIANA, A CORPORATION OF INDIANA.

ROTARY SNAP SWITCH.

Application filed April 9, 1926. Serial No. 100,867.

My invention relates to rotary snap switches and more particularly to an extremely small switch of this type.

- It is a purpose of my invention to provide 5 a rotary snap switch that is very compact, so that the same can be placed in position in fixtures and other devices where only a small amount of space is provided. In order to accomplish this a new and improved 10 construction of movable contact means is provided that occupies a minimum of space and which is so constructed that it will be within the limits of safety required of a device of this character.
- More particularly it is a purpose of my 15 invention to provide a switch mechanism having stationary contacts with a movable contact member cooperating with said stationary contacts and means for rotating said movable contact member comprising an operating member and an insulating member keying said operating member to the contact member, so that said contact member is rotated upon rotation of the operating 20 member. The movable contact member is preferably made in as small a manner as possible, preferably comprising a body portion having a central flange portion providing a channel therein and winged portions 25 that engage with the stationary contacts. The insulating key member preferably comprises a rectangular portion that engages between the flanges of the movable contact member and a smaller rectangular portion 30 that engages in a slot in the actuating member. The key member is preferably provided with a shoulder at the junction of the two rectangular portions against which an insulating washer is adapted to seat, said insulating washer having the end of a compression spring bearing thereagainst for 35 yieldingly holding the movable contact member in contact with the stationary contacts.
- Other objects and advantages of the 40 invention will appear as the description of the accompanying drawings proceeds. However, I desire to have it distinctly understood that I do not intend to limit myself to the exact details shown or described but that I intend to include as part of my invention all such obvious changes and modifications of parts as would occur to a person

skilled in this art and as would fall within the scope of the claims.

In the drawings:

Fig. 1 is a vertical sectional view of my improved switch mechanism taken on the line 1—1 of Fig. 2;

Fig. 2 is a view taken substantially on the line 2—2 of Fig. 1 looking in the direction of the arrows; and

Fig. 3 is a detailed elevation of the movable contact member and the insulating key member associated therewith.

Referring in detail to the drawings, my improved rotary switch mechanism comprises an insulating body portion 10 having a recess 11 therein that is provided with a substantially centrally located circular depression 12 and with an annular series of inclined shoulders or ratchet faces 13 having the gradually inclined portions 14 and the more sharply inclined portions 15. Engaging a pair of oppositely disposed faces 14 are the stationary contact members 16 which have outwardly extending portions 17 which lie in a plurality of planes and extend around the shoulders formed by the material 18 of the member 10 between the recess 11 and the recesses 19 in which the tubular portions 20 of the contact 16 lie, said tubular portions having the ends 21 of the conductors 22 mounted therein, said conductors 22 lying in grooves 23 in the body portion 10.

Cooperating with the body portion 10 is the cover member 24, an insulating gasket 25 being mounted between the cover 24 and the body portion 10 and said cover being held in position by any suitable securing means such as the screws 26. It will be noted that the cover 24 holds the contacts 16 in proper position due to the peculiar shape of the portions 17 thereof and that said contacts 22 are insulated from the cover by means of the gasket 25.

Cooperating with the stationary contact 100 16 is the movable contact member 27 which is provided with a central portion having a pair of flanges 28 defining a channel in which is received the rectangular end portion 29 of the insulating key member 30. The portion 29 is of an elongated rectangular shape so as to fit substantially within 105 the channel formed between the flanges 28.

The contact member 27 is further provided with a pair of wing like portions 31 which are inclined, as will be clear from Figs. 1 and 3, so that the forward portion thereof, 5 as the member rotates in a clockwise direction in Fig. 2, will be higher than the rear portion thereof. The insulating key member 30 is provided with a projecting portion 32 also of elongated rectangular form, but 10 of less width than the portion 29 defining shoulders at 33 against which the insulating washer 34 engages, said washer having an opening of such a shape as to receive the projection 32 and having the end portion of the 15 coil compression spring 35 bearing thereagainst. The reduced portion 32 of the member 30 is received within a slot 36 in the operating member 37, whereby the key member 30 is turned thus turning the contact member 27. As the contact member 27 is turned in a clockwise direction the same is cammed upwardly by the inclined faces 14 against the compression of the spring 35 and is dropped downwardly with snap action 20 when it engages with the faces 15 due to the compression of the spring 35.

Means is provided whereby the operating member 37 is rotated in only a clockwise direction. In order to do this the enlargement 30 or head 38 on the member 37 is provided against which the collar 39 which is slidably mounted on the member 37 bears, the collar 39 being held in engagement with the head 38 by the compression spring 35. A channel 35 or groove 40 is provided in the member 38 through which a tooth 41 on the collar 36 projects. The actuating finger piece 42 is provided with a transverse slot 43 with which the tooth 41 is adapted to engage, it 40 being obvious that upon rotation of the member 42 in one direction, the tooth 41 will engage with the slot 43, while upon rotation in the opposite direction, the inclined face 44 thereof will cause the same to ride out 45 of the slot 43, moving the member 36 away from the member 38 against the action of the spring 35. The actuating member 42 is held in position by means of the screw-threaded member 45 which screwthreadedly 50 engages with the member 37, the member 42 being rotatable on the member 45 except when the tooth 41 engages with the recess or slot 43. The actuating means is, of course 55 mounted upon the screwthreaded tubular member 46, which is mounted upon the cover member 44 in any suitable manner, and which is shouldered at 47 to provide a bearing for the head 38.

From the above, it will be seen that a very 60 compact and simple switch mechanism is provided. The body portion of the switch mechanism being extremely thin and small at the same time snap action is obtained and the required spacing of the contacts when in open circuit position also is obtained.

Furthermore, the actuating means is thoroughly insulated from the live contacts.

Having thus described my invention, what I desire to claim and secure by U. S. Letters Patent is:

1. In a switch mechanism, stationary contacts, a movable contact cooperating therewith, said movable contact having a channelled portion, an insulating member having a portion fitting in said channelled portion, means urging said insulating member toward said movable contact, and an operating member engaging said insulating member to rotate said insulating member and said movable contact. 70

2. In a switch mechanism, stationary contacts, a movable contact cooperating therewith, said movable contact having a recess therein, an insulating member having a portion engaging said recess, and an operating member having a slot in the end thereof, said insulating member having a projection seated in said slot. 80

3. In a switch mechanism, stationary contacts, a movable contact cooperating therewith, said movable contact having a channelled portion, an insulating member having a portion fitting in said channelled portion, and an operating member having a slot in the end thereof, said insulating member having a projection loosely seated in said slot. 90

4. In a switch mechanism, stationary contacts, a movable contact cooperating therewith, said movable contact having a recess therein, an insulating member having a portion engaging said recess, an operating member having a slot in the end thereof, a coil spring embracing said operating member and an insulating washer mounted on said insulating member and engaged by said spring, said insulating member having a projection entering said slot. 100

5. In a switch mechanism, stationary contacts, a movable contact cooperating therewith, said movable contact having a recess therein, an insulating member having a portion engaging said recess, an operating member having a slot in the end thereof, a coil spring embracing said operating member and an insulating washer mounted on said insulating member and engaged by said spring, said insulating member having a projection entering said slot and said insulating member having a shoulder against which said washer bears. 110

6. In a switch mechanism, stationary contacts, a movable contact member cooperating therewith, said contact member having a pair of laterally projecting wings for engaging said stationary contacts and a central flanged portion providing a channel in said member and operating means engaging in said channel for actuating said movable contact member. 120

7. In a switch mechanism an insulating 130

key member having oppositely extending rectangular portions of different widths defining a shoulder at the junction of said portions and an insulating washer mounted on said key member in engagement with said shoulder.

8. In a switch mechanism, stationary contacts, a movable contact member cooperating therewith, said contact member having a pair of laterally projecting wings and a central flanged portion providing a channel in said member, an insulating key member having a rectangular end portion entering the channelled portion of said contact member and resilient means pressing said key member into the channelled portion.

9. In a switch mechanism, stationary contacts, a movable contact member cooperating therewith, said contact member having a pair of laterally projecting wings and a central flanged portion providing a channel in said member, an operating member having a slot in the end thereof and an insulating key member having a rectangular end portion entering the channelled portion of said contact member, and having a reduced rectangular end portion engaging in said

slot defining a shoulder on said key member and means engaging said shoulder to retain said first named rectangular end portion in 30 said channelled portion.

10. In a switch mechanism, stationary contacts, a movable contact member cooperating therewith, said contact member having a pair of laterally projecting wings and a central flanged portion providing a channel in said member, an operating member having a slot in the end thereof, an insulating key member having a rectangular end portion entering the channelled portion of 40 said contact member, and having a reduced rectangular end portion engaging in said slot defining a shoulder on said key member, an insulating washer on said key member bearing against said shoulder and a coil 45 spring embracing said operating member and having one end in engagement with said washer to yieldingly press said movable contact member into engagement with said stationary contacts.

In witness whereof, I hereunto subscribe my name this 16th day of March A. D., 1926.

VICTOR R. DESPARD.
